Fig. 5

FIG. 1 is a front elevational view of a wheel center showing our new design;

FIG. 2 is a sectional view thereof taken along the line 2-2 of FIG. 1;

FIG. 3 is a sectional view thereof taken along the line 3-3 of FIG. 1;

FIG. 4 is a rear elevational view thereof; and

FIG. 5 is a perspective view thereof.

The characteristic feature of our new design resides in the alternately raised and depressed ribbed portions, each raised ribbed portion having an inwardly extending V-shaped cross-sectional configuration, and each depressed ribbed portion having an outwardly extending V-shaped cross-sectional configuration.

We claim:

The ornamental design for a wheel center, substantially as shown and described.
